UNITED STATES PATENT OFFICE

137,937

DESIGN FOR A MOUNTING CORNER

Albert W. Engel, Chicago, Ill.

Application February 23, 1943, Serial No. 109,611

Term of patent 14 years

(Cl. D61—1)

To all whom it may concern:

Be it known that I, Albert W. Engel, a citizen of the United States, residing in the city of Chicago, county of Cook, State of Illinois, have invented a new, original, and ornamental Design for a Mounting Corner, of which the following is a specification, reference being had to the accompanying drawing forming a part thereof.

In the drawing:

Figure 1 is a face or plan view of a mounting corner showing my new design.

Figure 2 is an edge view of the mounting corner shown in Figure 1.

My design for a mounting corner is characterized by its specific configuration in combination with the type and particular arrangement of the surface ornamentation as applied thereto, the drawing being lined for color and the opposite side being plain.

I claim:

The ornamental design for a mounting corner, substantially as shown and described.

ALBERT W. ENGEL.
